CLAIM

We claim the ornamental design for a cartridge component, as shown and described.

DESCRIPTION

FIG. 1 is a front, top right perspective view of a cartridge component illustrating our new design;

FIG. 2 is a top plan view of the design of FIG. 1;

FIG. 3 is a bottom plan view of the design of FIG. 1;

FIG. 4 is a left side elevational view of the design of FIG. 1;

FIG. 5 is a right side elevational view of the design of FIG. 1;

FIG. 6 is a front elevational view of the design of FIG. 1;

FIG. 7 is a rear elevational view of the design of FIG. 1;

FIG. 8 is a rear, top left perspective view of the design of FIG. 1;

FIG. 9 is a front, bottom right perspective view of the design of FIG. 1; and,

FIG. 10 is a rear, bottom left perspective view of the design of FIG. 1.

1 Claim, 10 Drawing Sheets
